United States Patent Office

Des. 177,638
Patented May 8, 1956

177,638

TOY FORT OR SIMILAR ARTICLE

Audrey A. Namowitz, New York, N. Y., assignor to Toy-master Products Company, Inc., Clifton, N. J., a corporation of New Jersey

Application August 25, 1955, Serial No. 37,662

Term of patent 14 years

(Cl. D34—15)

Fig. 1.

Fig. 2.

Fig. 1 is a perspective view of the toy fort or similar article showing my new design; and

Fig. 2 is a sectional view thereof, taken along the line 2—2 of Fig. 1.

I claim:

The ornamental design for a toy fort or similar article, as shown.
